[57] CLAIM

The ornamental design for a multi-purpose tool, as shown and described.

DESCRIPTION

FIG. 1 is a front-left-top perspective view of a multi-purpose tool, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front elevational view of an embodiment of the multi-purpose tool, with a knife blade, two saw blades and a pair of scissors pivoted from the handle of the multi-purpose tool of my new design.
